UNITED STATES PATENT OFFICE.

GEORGE P. THOMAS, OF GLENSHAW, PENNSYLVANIA.

PUNCHING MACHINERY.

1,311,539.

Specification of Letters Patent. Patented July 29, 1919.

Application filed August 30, 1918. Serial No. 252,071.

To all whom it may concern:

Be it known that I, GEORGE P. THOMAS, residing at Glenshaw, in the county of Allegheny and State of Pennsylvania, a citizen of the United States, have invented or discovered certain new and useful Improvements in Punching Machinery, of which improvements the following is a specification.

10 My invention relates to machinery for punching rivet holes through structural blanks, and while unlimited to the punching of any particular blanks, it is illustrated herein in its adaptability to machinery for punching plates.

Punching machinery of the character contemplated herein includes a punch, a work-supporting table on which a blank rests while being fed through the punch, 20 and a spacing table upon which the blank rests as it leaves the punch, and also upon which the longitudinal intervals of advance of the work are controlled.

To keep a blank in proper alinement as it is passed through the punch, there is mounted on the spacing table a spacing carriage adapted to be attached to the forward end of a blank and to run upon suitable tracks carried by the spacing table, and in 30 a similar manner a tail carriage, attached to the rear end of a blank, runs upon the work-supporting table. Between these two carriages the blank moves through the punch without lateral deviations from a straight line. However, to punch holes in the rear 35 end of the blank it is necessary to release the tail carriage from the blank, with the result that the rear end of the blank may move laterally and cause the holes to be 40 punched in wrong positions.

The object of my invention is to provide 45 punching machinery of the character already explained with means for preventing lateral displacement of a blank after the tail carriage has been released from the blanks. A further object is to provide an improved tail carriage.

In the accompanying sheets of drawings, 50 which form part of my specification, I have illustrated the preferred embodiment of my invention. Figure 1 is a plan view of the punching machinery; Fig. 2 a side view thereof; Fig. 3 a sectional view to enlarged scale taken on the line III—III, Fig. 1; Fig. 55 4 a sectional view taken on the line IV—IV,

Fig. 3; Fig. 5 a plan view of the tail carriage; Fig. 6 a sectional view taken on the line VI—VI, Fig. 5; and Fig. 7 a sectional view taken on the line VII—VII, Fig. 6.

In the punching machinery which I provide the punch may be of any desired type. As diagrammatically represented in Fig. 2, it comprises a frame 1 provided with an anvil 2, and with a reciprocating head 3, to which there are respectively attached usually a plurality of dies 4 and punches 5. The spacing table shown at the right hand side of the punch 1 may consist of a plurality of supports 6 on which there are mounted a pair of I-beams 7 which form tracks for the spacing carriage, and which also form supports for transversely extending shafts 8 provided with rotatably mounted work-supporting rolls 9. Any suitable form of spacing carriage 10 may be mounted upon the spacing table, such for example as the type of carriage shown in my Letters Patent No. 835,123, the carriage being provided with a suitable clamp 11 for engaging the forward end of a plate or other structural blank 12.

The work-supporting table at the left side of the punch 1 may be constructed the same as the spacing table just explained, the work-supporting table consisting of a plurality of supports 13, I-beams 14, shafts 15 and work supporting rolls 16. As far as some features of my invention are concerned, any desired form of tail carriage may be provided for engaging the rear end 90 of the blank 12 to hold it in alinement as it passes through the punch. However, I preferably provide a tail carriage of the character shown particularly in Figs. 5, 6 and 7.

The carriage shown in these figures comprises a base 17 adapted to slide longitudinally upon, and to be readily removed vertically from a guide rail in the form of an I-beam 18 carried upon the work supporting table between the I-beams 14. Pivoted on a horizontal axis to the rear end of the base 17 there is a forwardly projecting arm 19, the vertical movement of which may be limited by an adjustable stop consisting of a nut 20 having screw-thread engagement with a bolt 21 pivoted at its lower end to the base 17. As seen in Fig. 6, the bolt 21 projects through the arm 19 and the nut 20 engages such bolt at its outer end so that the 110

arm cannot be raised higher than the lower face of the nut. At the forward end of the arm 19 a clamping member is provided to coöperate with the base 17 to engage the blank. This clamping member preferably comprises a horizontally disposed shaft 22, rotatably mounted in the outer end of the arm 19, and provided at its outer ends with a pair of eccentric cylindrical extensions 23, 10 on each of which extensions there is mounted a roller 24, the periphery of which rollers may be knurled or otherwise roughened. To one of the projections 23 there is keyed an upwardly extending arm 25, which, when 15 the tail carriage engages a blank, lies in a forwardly inclined position, as indicated in the drawing. The arm 25 may be moved rearwardly by hand to release a blank, but for this purpose there is preferably provided 20 adjacent to the punch 1 a finger 26 adapted to engage the arm 25 as the blank is advanced through the punch.

The tail carriage which I have just described is simple in construction and light in 25 weight, and may readily be removed from the guide-rail 18 after such carriage has been detached from the blank. Thus, when the 30 punching of one blank is nearing completion, another blank may be laid upon the work-supporting table, and a second tail carriage be attached to it so that there need be no loss of time in the punching operations by reason of the attachment of a tail carriage to the successive blanks.

35 For centering a plate 12 or other blank upon the work-supporting table, such table may be provided with suitable blank-centering means. As specifically shown herein, the table may be provided with oppositely disposed centering clamps 35 slidably mounted upon arms 36 projecting laterally from the I-beams 14, such clamps having screw thread engagement with a rotatably mounted shaft 37 oppositely threaded at its ends and having 40 a hand wheel 38 attached to it. Two pairs of independently operable clamps spaced at a suitable interval are shown in Fig. 1. When a plate is placed on the table the shafts 37 are independently rotated to 45 cause the clamps to simultaneously move toward the center line of advance of a blank, and the clamps, engaging the sides of the blank, bring the blank to proper punching position.

50 As already explained the rear end of a blank, after the tail carriage has been released from it, may move laterally with the result that the end holes will not be punched in their proper positions. To overcome this 55 difficulty means are provided to guide the rear end of the blank after the tail carriage has been released. Such means preferably comprise a supplementary tail guide arranged on the spacing table side of the 60 punch, and adapted to maintain the rear 65

end of the blank in punching alinement during the punching of the end holes.

As shown particularly in Figs. 3 and 4, the supplementary tail-guide preferably comprises a guideway in the form of an 70 angle 27 and a clamp 28, slidably mounted thereon and provided with a set screw 29. The guideway or angle 27 is preferably mounted for lateral adjustment upon a pair of arms 30 projecting from one side of one 75 of the spacing table beams 7. The adjustable attachment of the angle 27 to the arms may be by means of bolts 31, which engage the horizontal leg of the angle and also engage fingers 32 extending beneath the horizontal flanges of the arms 30.

In the operation of the punching machinery, a plate or other blank to be punched is laid upon the work table, and, when brought into proper punching alinement by means of 85 the centering clamps 35, such clamps may be slightly loosened from the side of the blank and the blank pushed forwardly in position to punch the end holes, the clamps guiding the blank to such position. The blank may 90 then be attached to the spacing carriage 10 and to the tail carriage. The spacing carriage 10 is then advanced at the required spacing intervals and the punch is intermittently reciprocated to effect the desired 95 punching of the plate. Near the end of the punching operation the tail carriage is released from the blank 12, this being done by the arm 25 of the tail carriage striking the trip finger 26 adjacent to the punch. Prior 100 to this disengagement of the tail carriage, a workman attaches the clamp 28-29 to the side of the plate, and if necessary adjusts the guideway 27 laterally so that it will be in proper position to receive the clamp and 105 guide the rear of the plate. This supplementary tail-guide holds the rear end of the plate in proper punching alinement until the completion of the punching operation.

According to the provisions of the patent 110 statutes, I have described the principle and operation of my invention together with the punching machinery which I now consider to represent the best embodiment thereof. However, I desire to have it understood that, 115 within the scope of the appended claims, my invention may be practised by other forms of construction than that particularly shown and described.

I claim as my invention:

1. The combination with a punch for perforating structural blanks, and spacing and work-supporting tables on opposite sides of said punch, of a spacing carriage on said spacing table adapted to engage the forward 120 end of a blank, a tail carriage on said work-supporting table adapted to engage the rear end of a blank, and a supplementary tail guide on the spacing table side of said punch, 125 said guide comprising means for engaging 130

a blank and for holding said blank in punching alinement after said tail carriage has been released from the blank.

2. The combination with a punch for perforating structural blanks, and spacing and work-supporting tables on opposite sides of said punch, of a spacing carriage on said spacing table adapted to engage the forward end of a blank, a tail carriage on said work-supporting table adapted to engage the rear end of a blank, and a supplementary tail guide comprising a guideway on the spacing-table side of said punch and a clamp slidably engaging said guideway and adapted to engage the rear end of a blank, said supplementary guide being adapted to hold a blank in punching alinement after said tail carriage has been released from the blank.
3. The combination with a punch for perforating structural blanks, and spacing and work-supporting tables on opposite sides of said punch, of a spacing carriage on said spacing table adapted to engage the forward end of a blank, a tail carriage on said work-supporting table adapted to engage the rear end of a blank, a laterally adjustable guideway borne by and extending parallel with said spacing table, and a clamp adapted to engage a blank and slidable upon said guideway.

4. The combination with a punch for perforating structural blanks, and spacing and

work-supporting tables on opposite sides of said punch, of a spacing carriage on said spacing table adapted to engage the forward 35 end of a blank, a tail carriage on said work-supporting table adapted to engage the rear end of a blank, means operative on the advance of the blank and carriages for releasing said tail carriage from the blank, and 40 a supplementary tail guide on the spacing table side of the punch, said supplementary guide comprising means for engaging a blank and for holding it in punching alinement after said tail carriage has been released from the blank. 45

5. The combination with a punch for perforating structural blanks, and a work-supporting table adjacent to said punch, of a tail-carriage track parallel with said table, 50 and a tail carriage comprising a base slidable upon and readily removable from said track, a forwardly projecting arm pivoted on a horizontal axis to the rear end of said base, adjustable means for limiting the vertical 55 movement of said arm, and a clamping member pivoted to the outer end of said arm and coöperating with said base to engage a blank.

In testimony whereof I have hereunto set my hand.

GEORGE P. THOMAS.
